PIETRO CINQUINI, OF WEST MERIDEN, CONNECTICUT, ASSIGNOR TO
BRADLEY & HUBBARD, OF SAME PLACE.

Design No. 4,085, dated May 31, 1870.

DESIGN FOR A CHANDELIER.

The Schedule referred to in these Letters Patent and making part of the same.

To all whom it may concern:

Be it known that I, PIETRO CINQUINI, of West Meriden, in the county of New Haven and State of Connecticut, have invented a new Design for Chandelier; and I do hereby declare the following, when taken in connection with the accompanying illustration and the letters of reference marked thereon, to be a full, clear, and exact description of the same, and which said illustration constitutes part of this specification, and represents a perspective view of the chandelier.

This invention relates to a design for chandeliers for either gas or oil, and, like other chandeliers, is composed of two parts, the center or base, and brackets, the same brackets being used independent of the center for attachment to the wall.

The design consists in the peculiar form or outline

of the center or base of the chandelier; also of the bracket, whether attached to the base or used independent.

A side view of the bracket is clearly shown at A, in the illustration, and the general outline or design of the center is also clearly seen, the base from which the brackets start being plain, with molded ornamentation above and below.

I claim as my invention—

The design for chandelier center and bracket, as fully shown in the accompanying photographic illustration, whether used separately or together.

PIETRO CINQUINI.
